UNITED STATES PATENT OFFICE.

DAVID PETRI-PALMEDO, OF HOBOKEN, NEW JERSEY.

METHOD FOR CASTING LINES OF SINGLE TYPE.

No. 884,298.

Specification of Letters Patent.

Patented April 7, 1908.

Application filed July 18, 1907. Serial No. 384,387.

To all whom it may concern:

Be it known that I, DAVID PETRI-PALMEDO, a citizen of the United States, and a resident of the city of Hoboken, in the 5 county of Hudson and State of New Jersey, have invented certain new and useful Improvements in Methods for Casting Lines of Single Type, of which the following is a specification.

10 This invention relates to the art of casting printers' type from matrices, and in particular to the art of casting such type in assembled lines in the order that they are to appear in print. For this purpose there are at 15 present two methods preëminently in use. In one of these which is embodied in the Mergenthaler linotype and kindred machines individual matrices are assembled in the proper order in line in front of a common 20 mold, and the type is cast from them simultaneously, yielding a solid line of type or "slug."

In the other method which is embodied 25 in the monotype the individual types are cast one at a time successively in previously determined proper order in an adjustable mold, yielding lines of single type.

It is the object of this invention to thus 30 combine the aforesaid methods to a degree insuring the advantages of both without their inherent disadvantages, in providing a method of casting simultaneously the individual types constituting a line as it is to appear in print. Provision is also made in 35 this my improved method for automatic justification, as is done in the other methods.

My method will be best understood in 40 connection with an illustration of one of several forms of apparatus that may be employed in its embodiment which is shown in the accompanying drawings of which—

Figure 1 is a perspective view of a line of 45 matrices assembled according to my invention without any provision for justification. Fig. 2 is a vertical cross section on line 2—2 Fig. 1. Figs. 3 and 4 are similar sections showing the parts in different positions. Fig. 5 is a vertical longitudinal section on lines 5—5 of Figs. 3 and 4. Fig. 6 is a perspective 50 view of a line of matrices and justifying wedges assembled in accordance with my invention, the figure corresponding to Fig. 1. Figs. 7 and 8 are perspective sectional views 55 on lines 7—7 and 8—8 respectively of Fig. 6. Figs. 9 and 10 are repetitions of Fig. 7 showing the parts in different positions. Fig. 11

is a longitudinal section on line 11—11 Fig. 6, the figure corresponding to Fig. 5.

Similar letters refer to similar parts throughout the several views.

A and A' in the drawings are blocks, abutments, or "jaws" mounted in a suitable manner in a holder or frame. B, B, B are matrices or rather matrix-molds consisting each of a plate equal in thickness to the thickness of the type that is to be produced from it, and having a slot b cut into its lower edge equal in depth to the height of the type, which slot will hereinafter be referred to as the "mold slot." At the bottom of the 70 mold-slot the intaglio letter b' that is to produce the printing face of the type is formed, or in other words, the matrix proper. The matrices have ears b² by which they may be supported in the frame between the 75 jaws A and A'. The matrices have also, under certain conditions, perforations to which I will refer later.

The matrices B, B are assembled between the jaws A A' by hand or by a suitable 80 assembling mechanism in such a manner that each of them covers up the mold-slot of the neighboring one as shown, for instance, in Fig. 2. The jaws A and A' performing this office for the extreme right or left matrices.

In order to assemble the matrices B, B so that when they are assembled each one of them covers up the mold-slot of the neighboring one, the plan may be adopted as shown in Fig. 2, 90 namely; the bars constituting the frame or holder are, by assemblage, wider apart than the width of the matrices and in inserting the latter between the said bars, they are placed to alternately abut against the front 95 and the rear bars.

After the matrices are assembled as shown in Fig. 1 the jaws A and A' are firmly pressed together locking the matrices between them making tight joints. In this manner a 100 series of independent type molds is formed which are suitable for receiving molten type metal. This is injected into said molds in the well known manner by means of a pump (not shown) through a series of holes c, Figs. 2, 105 3, 7 and 8, terminating in two slots c' in a sprueplate C secured to the mouth D of a melting pot.

After type metal has been injected into the mold cells and solidified the pressure on the jaws is slightly relieved, and the type may then be removed from the matrix-

molds in the direction of the height of the type by the retraction of the pot mouth and sprueplate the type adhering thereto by the sprue formed in the slots c' . The individual type may then be cut off from the sprues and collected into line by suitable means.

Thus far described my method of casting lines of single type presents itself in its simplest form. The collecting of the cast 10 type after their detachment from the sprues, however, may present practical difficulties to avoid which I effect the removal of the type preferably in the following manner: After the type is cast and the pressure on the jaws 15 is slightly relieved the type is withdrawn in the direction of its height by the retraction of the sprueplate only far enough to withdraw the face of the type from within the matrix proper or intaglio letter at the bottom 20 of the mold-slot; next the matrices are by suitable means shifted relatively to each other so as to bring all the mold slots to register as shown, for instance, in Fig. 4. By this the sprues are broken off from the 25 bottom of the type. The type F, Figs. 3 and 5 can now be removed by means of an ejector blade E sidewise through an opening in the jaw A as indicated in Fig. 5.

The sprue-slots c' are necessarily narrow 30 and many of the matrices being thin especially for small type the connection of the metal joining each individual type to the sprue is sometimes very small so that there is likelihood of the sprue being torn off in re- 35 moving the type either wholly or partly by the retraction of the sprueplate as above assumed. To avoid this I prefer to form recesses f in the type F by providing two blades G and G' , (Figs. 1 and 2) passing through the 40 mold-cells. Inasmuch as these are located in alternate planes because of each matrix covering the mold slot of its neighbor, perforations b^3 , b^3 are provided in the matrices for the blades G, G' so that they can extend 45 from one end of the line of matrices to the other. After the type metal has been injected and has solidified these blades G, G' are withdrawn; after that the matrices are brought to register breaking the sprues, as 50 shown in Fig. 3; next, one of the blades, say G, is reinserted into the recess f of the types and by a downward pressure on its two ends the face of the type F is withdrawn from within the matrix proper b' whereupon the type can 55 be ejected sidewise as before, the blade G incidentally serving as a guide for both the ejector blade E and the type F.

My method as so far described does not 60 provide for justification, and would be suitable only for work in which the lines assume the proper length without such justification as in plain figure work and the like, where the type is designed according to the so-called unit system; or justification would have to be 65 effected subsequently to casting the type.

To provide for justification I employ thin spacer matrices H of the same pattern as the letter matrices B, made, however, wedge shaped, that is, thinner on one side than on the other to coöperate with long wedges I inserted into the line alongside the space matrices H, much in the same manner as the "spacebands" in the Mergenthaler linotype and kindred machines. The wedges I have a longitudinal slot i of less width than the depth 70 of the mold slots b , enabling them to be slipped over blades or bars G^2 , G^3 , and G^4 . These blades or bars pass through openings in the matrices and form part of the front and rear walls of the mold cells, as shown in Figs. 7 80 and 8. It will be seen that by this arrangement a mold cell is formed for a justifying lug next to the mold cell of the spacer matrix and in full communication therewith, and this mold cell can be widened and narrowed 85 according to the amount of justification needed. If the type is large and the spacing between the words large also accordingly I place another thin spacer matrix H' after the long wedge I, with its mold cell in the same 90 plane as that of its mate H. This spacer matrix H' need not, however, be wedge shaped and can be of varying thickness. It will be seen that the two spacer matrices H and H' and the long wedge between them in 95 conjunction with the bars G^2 , G^3 , G^4 will produce independent spaces as shown, for instance, at K, Fig. 11. For small type I find it convenient to do without the spacematrix H', in which case the justified space will be 100 produced integral with the last letter of the preceding word as shown at K', Fig. 11.

Two of the blades or bars (G^3 and G^4) have each a rib g' projecting into the mold cells to form recesses in the type said ribs taking the 105 place of the blades G and G' previously mentioned. After the line of matrices has been assembled with space matrices and justifying wedges in proper places the bars G^2 , G^3 , G^4 are inserted, the wedges I are driven into the 110 line spreading the matrices till they fill completely the space between the abutments or jaws A and A'; next the molten metal is injected. After solidification the bars G^2 , G^3 , G^4 are withdrawn, the matrices shifted so as 115 to bring the mold slots b to register, as shown in Fig. 9, and then another bar or blade G^5 is inserted that fits the recesses f in the type F but is smaller in height than the bars G^2 , G^3 , G^4 so that by a pressure on both its ends 120 it may be moved downward in the openings of the matrices, taking the types with it, thus withdrawing them from the matrices proper, as shown in Fig. 10. It will be noticed that the wedges I remain in place during this latter operation and descend with the type. Next the wedges I are withdrawn from between the matrices sufficiently 125 to clear the mold cells, and finally the line of justified single type is ejected sidewise as 130

shown in Fig. 11, the bar G⁵ serving as a guide both for the type F and the ejector blade E.

I claim:

- 5 1. The method of casting lines of single type as they are to appear in print consisting in assembling mold matrices between fixed abutments so that each matrix forms a mold side wall for each neighboring one and leaving individual mold cavities between them, injecting molten metal simultaneously into all the individual mold cavities formed between the assembled mold matrices and subsequently removing the cast line of single 10 type from the molds.
- 15 2. The method of casting lines of single type as they are to appear in print consisting in assembling slotted mold matrices between fixed abutments so that each mold matrix forms a mold side wall for each neighboring one and covers the mold slot of the neighboring matrix and leaving individual mold cavities between the assembled mold matrices, injecting molten metal simultaneously into all the individual mold cavities formed between the assembled mold matrices, withdrawing the type partly from the matrices in the direction of their height, shifting the matrices relatively to each other to make the 20 mold slots register, and finally ejecting sidewise the line of single type.
- 25 3. The method of casting lines of single type as they are to appear in print consisting in assembling slotted mold matrices between fixed abutments so that each matrix forms a mold side wall for each neighboring one and covers the mold slot of the neighboring matrix and leaving individual mold cavities between the assembled matrices, inserting recess forming blades passing through the mold 30 cells of the slots of the assembled matrices,
- injection molten metal simultaneously into all the individual mold cells, allowing the metal to solidify, withdrawing the recess forming blades, shifting the matrices relatively to each other to make the mold slots register, reinserting one of the blades into the recesses of the cast type, withdrawing partly the type from the matrices in the direction of their height, and finally ejecting sidewise the whole line of single type. 45
4. The method of casting justified lines of single type as they are to appear in print consisting in assembling slotted mold matrices between fixed abutments so that each matrix forms a mold side wall for each neighboring one covering the mold slot of the adjoining matrix and leaving individual mold cavities between the assembled matrices, inserting wedge shaped space matrices, justifying 50 wedges and blades between the matrices, justifying the line of matrices by driving the wedges, inserting recess forming and cell forming bars, injecting then molten metal simultaneously into all the individual mold 55 cells formed by the assembled letter matrices, space matrices, and justifying wedges and blades, allowing the metal to solidify, withdrawing the blades, shifting the matrices to make the mold slots register, inserting a 60 blade into the recesses of the cast type, withdrawing the type partly from the matrices in the direction of their height, and finally ejecting sidewise the whole justified line of single type. 65

Signed at Hoboken in the county of Hudson and State of New Jersey this thirteenth day of July A. D. 1907.
